JOURNAL BOX LID

Geoffrey W. Cope, Williamsville, N.Y., assignor to Symington Wayne Corporation, Salisbury, Md., a corporation of Maryland

Filed May 25, 1959, Ser. No. 815,541
15 Claims. (Cl. 308—47)

This invention relates to lids for railway journal boxes.

An obstacle long confronting the development of journal box lids has been the limitation imposed on a lid's closing pressure by the necessity for opening the lid at frequent intervals to permit inspection of the interior of the journal box to which it is applied. Were it simply a matter of increasing the pressure after the lid is closed, the solution would be found in any of the numerous so-called high pressure lids proposed or in service. However, all such prior lids have depended for increasing their pressure on levers or similar means requiring special handling by inspectors and with the number of inspectors legion and the lids in interchange service of many types, it has been a practical impossibility to have any lid given special handling. The result has been that the full capabilities of high pressure lids heretofore have been used intermittently, if at all.

The shortcomings of present high pressure lids and the concerted effort now being made to eliminate all possible causes of hot boxes, only serve to emphasize the need for a lid which will exert a high pressure when closed but require no special handling and may be opened and closed with a force comparable to that needed for an ordinary lid. The primary object of this invention is to provide such a lid.

Another object of the invention is to provide a journal box lid which applies increased pressure when closed but neutralizes the increase during opening or closing by a dead man lever operating automatically on release to restore the maximum pressure of which the lid is capable.

An additional object of the invention is to provide a high pressure journal box lid in which the handle by which the lid is opened and closed also is the handle of a lever, which during opening and closing of the lid reduces the required force to the order of that needed for an ordinary lid and on release automatically restores the maximum force exertable by the lid.

Another object of the invention is to provide a high pressure journal box lid of the character described which is simple and rugged in construction and so mounts its lever as to be non-rattling in operation.

Other objects and advantages of the invention will appear hereafter in the detailed description, be particularly pointed out in the appended claims and be illustrated in the accompanying drawings, in which:

FIGURE 1 is a side elevational view of a preferred embodiment of the journal box lid of the present invention with the lid and associated structure tilted out of normal so that the cover of the lid is vertical;

FIGURE 2 is a fragmentary front elevational view of the structure of FIGURE 1;

FIGURE 3 is a fragmentary vertical sectional view on an enlarged scale taken along the lines 3—3 of FIGURE 2;

FIGURE 4 is a fragmentary transverse sectional view taken along the lines 4—4 of FIGURE 3; and

FIGURE 5 is a fragmentary view from the underside of the upper end portion of the lever.

Referring now in detail to the drawings in which like references designate like parts, the improved journal box lid of this invention is of general application to railway journal boxes.

The journal box lid illustrated as exemplary of the in-

2

vention is in many respects similar to a typical, ordinary or conventional lid of the articulated type now in general use. Thus, the illustrated lid has a hood 1 connectable by a pintle pin 2 to a hinge lug 3 of a journal box 4 and connected for limited relative angling or articulation to a cover 5 adapted to seat on a lid face 6 on the journal box about a front opening 7 therein and so cover or close that opening. As in a typical articulated lid, the articulated connection between the hood 1 and cover 10 5 may be formed by a web 8 connecting the transversely spaced, longitudinally extending or downstanding legs 9 of the hood and having an outwardly facing, spherically concave socket 10 seating in a cavity or depression 11 formed centrally in the outer face 12 of the cover 5, the socket in turn seating an inwardly convex or facing, correspondingly spherical ball or protuberance 13 formed in a bridge member 14 straddling the web 8 between the legs 9 and welded or otherwise fixed or secured at or adjacent its longitudinal or vertical extremities in the cover above and below the cavity 11.

For applying the pressure by which the cover 5, when closed, is held tight against the lid face 6 on the journal box 4, there is employed a torsion or other suitable lid spring 15 which applies a closing force to the cover by reacting against the hinge lugs 3. Like that used in one type of ordinary or conventional lid, the illustrated lid spring 15 is of downwardly opening U-shape, and has the lower ends 16 of its transversely spaced legs 17 in-turned or toed-in and bearing against the outer face 12 of the cover 5 substantially midway between the latter's vertical extremities and at either side of the cavity 11. The spring 15, on a horizontally or transversely extending cross rod 18 forming its upper end and integral with and connecting the upper extremities of its legs 17, carries 35 or mounts a roller 19 which is adapted to engage and ride on the peripheral surface 20 of the hinge lug 3 and through which the spring reacts against the journal box 4, the illustrated lug surface conforming to the contour shown in Blattner Patent No. 2,675,278 and now standard for journal box hinge lugs. The coils 21 on the legs 17 intermediate their ends in their turn seat against seats 22 provided for that purpose on the inner surface or face 23 of the hood 1.

Acting outwardly against the hood 1 through its coils 45 21 and inwardly against the cover 5 through the lower ends 16 of its legs 17 and reacting through the roller 19 against the hinge lug 3, the illustrated spring 15 is adapted to apply, at the center of the cover, an inward or closing force which is the resultant of or difference between the inward and outward forces exerted by the spring respectively on the cover and on the web 8 connecting the legs 9 of the hood 1. In the ordinary lid, the closing force exerted by the lid spring on the cover usually will not exceed 60 pounds, this upper limit being imposed by the necessity, predicted on the strength of the average inspector, that the lid be openable by a force of about 25 to 30 pounds which, in the ordinary lid is applied to a handhold formed on the cover below the portion thereof covering the front opening in the journal box. Inadequate for effective sealing of the front opening under all service conditions, this limitation on the closing force of the ordinary lid, which renders it ineffective for sealing under all service condition, is avoided in the lid of this invention in which the spring 15 is enabled to be of sufficient strength to apply a closing force on the cover practically double that obtained in the ordinary lid and ample for effective sealing, without correspondingly increasing the force required for opening and closing.

In attaining its objective, the lid of this invention dispenses with the usual handhold on the cover and, instead, uses, as its operating handle, lever means 24 fulcrumed

on the hood 1 or other suitable part of the lid and operative to apply a force opposing and reducing that exerted by the spring 15 on the hinge lug 3. The lid deriving the closing force on its cover 5 from the reactance of the spring 15 against the hinge lug 3, any reduction in the force exerted by the spring on the hinge lug will reduce the closing force on the cover. Thus, as opposed to an ordinary lid in which the static closing force fixes the opening force required to be applied to the cover to open the lid, the closing force on the cover 5 of the lid of this invention is progressively reduced or decreased with increase in the force on the lever means 24 by reduction in the force exerted by the spring 15 on the hinge lug 3, with the result that the outward force required to be applied to the cover through the lever and hood to open the lid is far less than the static closing force on the cover. Not only does the lever means 24 effect this reduction in the closing pressure of the spring 15 on the cover 5 without appreciable movement prior to opening, but it maintains this reduction as the lid is swung between closed and open positions by moving relative to the hood 1 or other part of the lid on which it is fulcrumed. It is this principle that is utilized in the lid of this invention to reduce a static closing force far in excess of that employable in an ordinary lid to the point at which the lid may be opened by a force within the required 25-30 pound range without extending the lever means beyond the vertical confines of the ordinary lid and without requiring special handling either during opening or closing or after the lid is closed. Specifically, it is possible in a lid of the relative dimensions of the illustrated embodiment to increase the strength of the spring 15 so that the static pressure on the cover 5 is some 98 pounds and nonetheless open the lid with a force of 29.3 pounds.

The lever means 24, in its simplest and preferred form, is a "dead man" or automatic return lever which, when released, automatically returns to normal position and restores the force of the spring 15 to maximum. In the illustrated embodiment, the lever 24 is mounted on or carried by and connected adjacent its upper end 25 to the hood 1 for fulcruming on the outer surface or face 26 thereof. Centered laterally or transversely on and extending longitudinally of the hood 1, the lever 24 projects or extends below the legs 9 of the hood and also preferably below the straight lower edge 27 of the preferred rectangular cover 5 substantially to the level of the handhold on the cover of an ordinary lid. In the main substantially paralleling the cover 5, the lower part of the lever 24 conveniently is flared or widened adjacent its lower or free end 28 to provide a readily grippable handhold or handle portion 29. The lever 24, as a whole, may be of any cross-section suitable for rigidity, that shown, except for its handhold 29, being of channel section with a central web 30 reinforced by side flanges 31.

The connection between the upper end portion of the lever 24 and the hood 1 is made by a link or connector 32 which at the same time connects or links the lever to the upper end or portion of the spring 15 which reacts against the hinge lug 3, here the cross rod 18. In the illustrated form, the link 32 is an eyebolt, the eye 33 of which encircles the cross rod 18 between the two parts into which the roller 19 is axially divided or split, and the stem or shank 34 of which projects or extends, preferably normal to the substantially vertical front face 35 of the hinge lug 3, through aligned apertures or openings 36 and 37, respectively, in the front or outer wall 38 of the hood and the central web 30 of the lever. Beyond or outwardly of the web, the shank 34 of the eyebolt 32 carries a nut or like suitable means 39 for connecting the eyebolt to the lever and the latter to the hood 1. So linked, the lever 24 is adapted, during both opening and closing of the lid, to apply a retracting force to the upper end 18 of the spring 15 for reducing the force exerted by the latter against the hinge lug 3 by providing the lever with a pair of fulcrums vertically straddling, bracketing

or spanning its connection to the link 32, one an upper or opening fulcrum 40 and the other a lower or closing fulcrum 41. Fixed on the outer surface 26 of the hood 1 above and below the stem-receiving aperture 36 in the outer wall 38 thereof, the fulcrums 40 and 41, to enable them additionally to prevent the lever 24 from rotating out of its vertical position about the stem 34 of the eyebolt 32, each conveniently may be formed by a preferably cylindrically convex rib or ridge 42 outstanding from and extending horizontally or transversely of one of the members and normally seating in a correspondingly extending and concave groove 43 in the confronting surface of the other member, the ribs here being formed on the underside 44 of the lever 24 and the mating grooves in the outer surface 26 of the hood 1.

Respectively at or adjacent and downwardly of the upper end 25 of the lever 24 and together bracketing or straddling the stem 34 of the eyebolt 32 and the aperture 36 in the hood 1 through which the stem projects, the upper and lower fulcrums 40 and 41 enable the lever to apply an outward retracting or pulling force on the upper end 18 of the spring 15 and so decrease the force exerted by the spring on the hinge lug 3 incident to and without change in the normal motions by which the lid is swung open and closed. Thus the lever 24 will fulcrum about the upper fulcrum 40 on opening and the lower fulcrum 41 on closing, acting in the first instance as a second class lever and in the second as a first class lever. In each case the force exerted by the spring 15 against the hinge lug 3 is reduced by an amount equal to the force applied to the lower end 28 of the lever 24 multiplied by the mechanical advantage as measured by the quotient of the length of the lever arm divided by the reactance arm, the latter the distance between the center of the stem 34 and the particular fulcrum on which the lever is acting. In turn, as previously pointed out, this reduction in the force against the hinge lug 3 is accompanied by a reduction in the closing force on the cover 5 to the point at which the lid, despite the almost double static closing force on its cover, may be opened with a force comparable with that required for an ordinary lid. To take full advantage of the increase in the static closing force and at the same time avoid the machining to close tolerances that would otherwise be required, there preferably is bonded to the inner face 45 of the cover 5 a "Urethane" or like resilient sealing gasket 46, which in the closed position of the lid seats against the lid face 6 on the journal box.

While the lever 24 reduces the force applied by the spring 15 to the hinge lug 3, it is neither designed nor intended to counterbalance that force, so that the roller 19 at all times remains in contact with the periphery 20 of the hinge lug. Nonetheless, relative movement between the lever and both the hood 1 and the retractor or eyebolt 32 will occur, as the roller 19 is displaced outwardly toward the front wall 38 of the hood in rolling or moving, as the lid is opened or closed, between its closed position on the front face 35 of the lug and the latter's upper corner or apex 47. The apertures 40 and 41 in the hood and lever therefore are enlarged relative to the diameter of the stem 34 to accommodate the relative movement of the stem without binding.

With the lever 24 and link 32 in effect pivotally or rockably connected by virtue of the lateral play of the stem 34 in the lever aperture 37 and the relative pivoting preferably facilitated by interposing between the nut 39 and outer face 43 of the web 30 an inwardly dished Belleville or other suitable spring washer 49, there still remains the problem of preventing rattling of the lever in the closed position of the lid. It, of course, would be possible to tighten up the nut 39 to the point at which the lid spring 15 would exert an inward force therethrough on the lever and so hold the ribs or bearing elements 42 on the underside 44 of the latter in tight engagement with their grooves or seats 43 on the hood.

However, this would have the disadvantage of reducing correspondingly the maximum force exertable by the spring against the hinge lug 3 with attendant reduction in the static closing force on the cover 5. It therefore is preferred to employ additional spring means for normally holding the lever in tight engagement with the cover.

In the illustrated embodiment, the additional spring means is in the form of a coil spring 50 encircling the stem 34 of the eyebolt 32 inwardly of the outer wall 38 of the hood and acting between that wall and an annular shoulder 51 formed on the eyebolt between its stem and its eye 33. If, in addition, the cross rod-receiving opening 52 in the eye 33 is somewhat elongated axially of the stem 34, it is possible to turn the nut 39 in to the point at which the lever 24 is pulled tight against the hood 1 by the stem encircling, anti-rattling spring 50, without affecting either the pressure exerted by the lid spring 15 against the hinge lug 3 or the action of the lever in applying a retracting force to that spring during opening and closing of the lid. Once this adjustment is made, the nut 39 readily may be fixed in adjusted position by a cotter pin or like locking means 53 extending radially through the bolt 32 and an axial slot 54 provided for that purpose in the outer end portion of the stem.

The lever 24 not only permits a drastic increase in the closing force on the cover, but also facilitates the initial retraction of the upper end 18 of the lid spring 15 required to enable the lid to be mounted on a journal box. Thus, for this purpose, a temporary retainer pin may be driven between the confronting faces of the lever 24 and the hood 1 below the stem 34 of the eyebolt 32, so as to seat against and be held in place by the lower fulcrum 41 or, as indicated in the drawings, a U-shaped retainer 55 may be driven through suitable apertures in the upper end of the hood to engage the upper end of the spring directly at either side of the roller 19. In either case, crowbar (not shown) may readily be inserted between the lever and the cover to apply the force required further to retract the upper end of the spring to the point at which the temporary retaining means can readily be removed.

From the above detailed description, it will be apparent that there has been provided an improved journal box lid which, while openable and closable in the same manner and with substantially the same force as an ordinary lid, on closing automatically exerts on its cover a closing force far in excess of the maximum possible in the ordinary lid. It should be understood that the described and disclosed embodiment is merely exemplary of the invention and that all modifications are intended to be included which do not depart from either the spirit of the invention or the scope of the appended claims.

Having described my invention, I claim:

1. A journal box lid comprising a cover, spring means reactable against a hinge lug of a journal box for applying a closing force to said cover, and lever means operative on actuation to act on said spring means in opposition thereto for reducing the force exertable by said spring means on said lug and therethrough the closing force on said cover.

2. A journal box lid comprising a cover, spring means reactable against a hinge lug of a journal box for applying a closing force to said cover, and lever means operative on actuation to act on said spring means in opposition thereto for reducing the force exertable by said spring means on said lug and therethrough said closing force on said cover and on release automatically to restore said force.

3. A journal box lid comprising a cover, a hood connected for limited relative angling to said cover and connectable to a hinge lug of a journal box, spring means reactable against said lug for applying a closing force to said cover, and lever means fulcrumed on said hood and operative on actuation to act on said spring means in opposition thereto for reducing the force exertable by said

spring means on said lug and therethrough said closing force on said cover.

4. A journal box lid comprising a cover, a hood connected for limited relative angling to said cover and connectable to a hinge lug of a journal box, spring means reactable against said lug for applying a closing force to said cover, and lever means fulcrumed on said hood and linked to said spring means for reducing the force exertable by said spring means on said lug and therethrough said closing force on said cover by applying an opposing force to said spring means.

5. A journal box lid comprising a cover, a hood connected for limited relative angling to said cover and connectable to a hinge lug of a journal box, spring means reactable against said lug and acting on said cover for applying a closing force thereto, lever means fulcrumed on said hood, and link means connecting said lever means to an end portion of said spring means reactable against said lug, said lever means on fulcruming reducing the force exertable by said spring means on said lug and therethrough said closing force on said cover.

6. A journal box lid comprising a cover, a hood connected for limited relative angling to said cover and connectable to a hinge lug of a journal box, spring means reactable against said lug and acting on said cover for applying a closing force thereto, and lever means fulcrumed on said hood and operative on actuation to act on said spring means in opposition thereto for reducing the force exertable by said spring means on said lug and therethrough said closing force on said cover and on release automatically to restore said force.

7. A journal box lid comprising a cover, a hood connected for limited relative angling to said cover and connectable to a hinge lug of a journal box, spring means reactable against said lug and acting on said cover for applying a closing force thereto, lever means fulcrumable on said hood on any of a plurality of fulcrums spaced longitudinally thereof, and link means connected to an upper portion of said spring means and to said lever means intermediate said fulcrums, said lever means on fulcruming on any of said fulcrums exerting a retracting force reducing the force exertable by said spring means against said lug and therethrough said closing force on said cover.

8. A journal box lid comprising a cover, a hood connected for limited relative angling to said cover and connectable to a hinge lug of a journal box, spring means reactable against said lug and acting on said cover for applying a closing force thereto, lever means fulcrumable on said hood on any of a plurality of fulcrums spaced longitudinally thereof, and link means connected to an upper portion of said spring means and pivotally connected to said lever means intermediate said fulcrums, said lever means on fulcruming on any of said fulcrums exerting a retracting force reducing the force exertable by said spring means against said lug and therethrough said closing force on said cover.

9. A journal box lid comprising a cover, a hood connected for limited relative angling to said cover and connectable to a hinge lug of a journal box, spring means reactable against said lug and acting on said cover for applying a closing force thereto, a lever fulcrumable on said hood on any of a plurality of fulcrums extending transversely and spaced longitudinally thereof, and link means connected to an upper portion of said spring means and to said lever intermediate said fulcrums, said lever on fulcruming on any of said fulcrums exerting a retracting force reducing the force exertable by said spring means against said lug and therethrough said closing force on said cover.

10. A journal box lid comprising a cover, a hood connected for limited relative angling to said cover and connectable to a hinge lug of a journal box, spring means reactable against said lug and acting on said cover for applying a closing force thereto, a lever extending longi-

tudinally of said hood and projecting below said hood and cover, said lever having an upper portion connected for fulcruming on said hood on any of a plurality of fulcrums spaced longitudinally thereof, and a link connecting said lever intermediate said fulcrums to an upper end portion of said spring means, said lever on fulcruming on any of said fulcrums exerting an outward force reducing the force exertable by said spring means on said lug and therethrough said closing force on said cover.

11. A journal box lid comprising a cover, a hood connected for limited relative angling to said cover and connectable to a hinge lug of a journal box, spring means reactable against said lug and acting on said cover for applying a closing force thereto, a lever centered transversely on and extending longitudinally of said hood, said lever having an upper portion connected for fulcruming on said hood on any of a plurality of fulcrums spaced longitudinally thereof, and a link connecting said lever intermediate said fulcrums to an upper end portion of said spring means, said lever on fulcruming on any of said fulcrums exerting an outward force reducing the force exertible by said spring means on said lug and therethrough said closing force on said cover.

12. A journal box lid comprising a cover, a hood connected for limited relative angling to said cover and connectable to a hinge lug of a journal box, a torsion spring having an upper end reactable against said hinge lug and therebelow acting between said hood and cover for exerting a closing force on said cover, a lever centered transversely on and extending longitudinally of said hood below said hood and cover, said lever being fulcrumable on said hood on any of a plurality of fulcrums spaced longitudinally thereof, a link connecting said upper end of said spring to said lever intermediate said fulcrums, and spring means acting against said hood and inwardly on said link for urging said lever into engagement with said hood.

13. A journal box lid comprising a cover, a hood connected for limited relative angling to said cover and connectable to a hinge lug of a journal box, a torsion spring having an upper end reactable against said hinge lug and therebelow acting between said hood and cover for exerting a closing force on said cover, a lever centered transversely on and extending longitudinally of said hood below said hood and cover, said lever being fulcrumable on said hood on any of a plurality of fulcrums spaced longitudinally thereof, a link pivotally connected

to said upper end of said spring and to said lever intermediate said fulcrums, and spring means acting against said hood and inwardly on said link for urging said lever into engagement with said hood.

- 5 14. A journal box lid comprising a cover, a hood connected for limited relative angling to said cover and connectable to a hinge lug of a journal box, a torsion spring having an upper end carrying a multipart roller for reaction therethrough against said hinge lug and therebelow
10 acting between said hood and cover for exerting a closing force on said cover, a lever centered transversely on and extending longitudinally of said hood below said hood and cover, said lever being fulcrumable on said hood on any of a plurality of fulcrums spaced longitudinally
15 thereof, a link pivotally connected to said lever intermediate said fulcrums and to said upper end of said spring intermediate parts of said roller, and spring means acting against said hood and inwardly on said link for urging said lever into engagement with said hood.

20 15. A journal box comprising a cover, a hood connected for limited relative angling to said cover and connectable to a hinge lug of a journal box, a torsion spring having an upper end carrying a multi-part roller and reactable therethrough against said hinge lug and therebelow acting
25 between said hood and cover for exerting a closing force on said cover, a lever centered transversely on and extending longitudinally of said hood below said hood and cover, said lever being fulcrumable on said hood on any of a plurality of fulcrums spaced longitudinally there-
30 of, an eyebolt having an eye encircling said upper end of said spring intermediate parts of said roller and a stem projecting substantially normal to a front face of said hinge lug loosely through said hood and lever intermediate said fulcrums, axially adjustable means on said stem
35 outwardly of said lever for connecting said lever to said eyebolt and therethrough to said hood and spring, and a coil spring encircling said stem within said hood and acting inwardly between said hood and an abutment on said stem for urging said lever into engagement with said
40 hood without affecting the force exerted by said spring on said lug.
